W. F. WOLF

LOOSE LEAF BINDER

Filed March 3, 1928

FIG. 3.

WALTER F. WOLF.
INVENTOR

BY *Victor J. Evans*

WITNESS: *W. C. Martin*

ATTORNEY

UNITED STATES PATENT OFFICE.

WALTER F. WOLF, OF NEW YORK, N. Y.

LOOSE-LEAF BINDER.

Application filed March 3, 1928. Serial No. 258,932.

This invention relates to loose-leaf binders and is an improvement over my co-pending application Serial No. 239,537, filed December 12th, 1927.

5 The primary object of this invention resides in a binder post which may be inserted through the openings in the loose leaf sheets after they have been removed from the binders for locking the sheets in a bound condition against separation, and which differs 10 from the construction shown in the above pending application in that the binder post is threaded or screwed to a locked position rather than by driving the same into frictional locking position.

Another object of the invention is to provide a binder post which includes a screw threadedly connected to one of the original loose-leaf binding posts, and a tubular sleeve 20 provided with a clamping flange and which sleeve threads over said screw for setting up a clamping action between the sleeve and lower post section to hold the loose leaf sheets therebetween in a clamped condition, the 25 threads between the screw and the original post section being looser co-acting threads than those between the screw and the sleeve to facilitate of the connection of the screw with the post section prior to the turning of 30 the sleeve with respect to the stud when turning the sleeve to effect a binding of the sheets.

With these and other objects in view, the invention resides in certain novel construction and combination and arrangement of parts, the essential features of which are hereinafter fully described, are particularly pointed out in the appended claims, and are illustrated in the accompanying drawing, in which:—

40 Figure 1 is a perspective view of a plurality of loose-leaf sheets partially bound.

Figure 2 is a vertical sectional view on the line 2—2 of Figure 1.

Figure 3 is a detail perspective view of the 45 binder post in a separated condition.

Referring particularly to the drawing, the numeral 10 designates my improved binding post in its entirety, which includes a threaded screw 11 having a reduced threaded stud 12 extending from one end thereof, while the opposite end is provided with a kerf 13. The threads on the screw and stud are of the same direction for a purpose to be hereinafter explained.

45 Co-acting with the screw 11 is a tubular

sleeve member 14 which is internally screw threaded as at 15 for a portion of its length. The outer end of the sleeve member is provided with an annular flange 16 having a kerf 17 in the outer face thereof. The tubular sleeve member threads over the screw 11 and the threads therebetween are of a relatively tight fit compared to the fit of the threads on the stud 12 and the base post section 18 with which it connects.

60 In Figures 1 and 2 of the drawing, I have shown a plurality of loose-leaf sheets 19 partially bound between a pair of covers 20. The front cover of the loose leaf binder in which they were temporarily held until ready 65 for permanent binding has been removed but the back cover section 21 of the binder still remains associated with the loose leaves. The binder back 21 includes a base strip 22 in which a collar 23 is mounted adjacent 70 each end, and through which a threaded stud 24 extends. The threaded stud screws into the lower end of the base post section 25 of the binder proper which supports the other 75 sections which have been removed. In applying the improved binder post for permanent binding of the volume of loose-leaves, certain of the original binder post sections are removed, leaving the base post section and, or certain of the other post sections intact, depending upon the thickness of the 80 volume to be bound. As shown in the drawing, all of the original binder post sections have been removed with the exception of the base section 18. The operator proceeds to 85 threadedly connect the sleeve 14 with the screw and inserts the same in the aligned binder post openings 26 in the loose leaves. By imparting a turning movement to the flanged end of the sleeve member, the stud 12 90 will thread into the threaded socket 27 in the base post member 18, as the tight fit between the threads on the sleeve and screw allows the stud 12 to be screwed home before the sleeve begins to turn with respect to the 95 screw. When the stud 12 reaches the limit of its movement into the base post section 18, the tubular sleeve begins to move downward over the screw, until the flange is 100 tightly pressing upon the front cover 20. If necessary, a screw driver may be inserted in either of the kerfs 13 and 17 to increase the 105 clamping action between the parts. The studs 24 may now be removed and the binder back 21 separated from the bound sheets and 110

again used for temporarily receiving loose leaves for permanent binding.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In combination with a plurality of stacked loose-leaves, a binder post section extending partially through the thickness of said plurality of loose-leaves from one side of the same, a screw threaded to said post section, and a sleeve extending through the opposite side of said plurality of loose leaves and provided with internal screw threads for threading engagement with said screw, the threaded connection between said sleeve and screw being of a tighter fit than the threaded connection between said screw and post section.

2. In combination with a plurality of stacked loose-leaves having aligned binder post openings thereon defining a continuous passage therethrough, a binder post section extending partially through said continuous passage from one side of said loose-leaves and provided with a flange for engagement with one of the outer loose-leaves, said binder post section having a threaded socket therein, a screw provided with a reduced threaded stud in threaded engagement with said threaded socket, an internally screw threaded sleeve extending into said passage from the opposite side of said loose-leaves and threadedly engaging said screw, and a flange provided on the outer end of said sleeve for clamping engagement with the other outer loose-leaf.

3. In combination with a plurality of stacked loose-leaves having aligned binder post openings therein defining a continuous passage therethrough, a binder post section extending partially through said continuous passage from one side of said loose leaves and provided with a flange for engagement with one of the outer loose-leaves, said binder post

section having a threaded socket therein, a screw provided with a reduced stud in threaded engagement with said threaded socket, an internally screw threaded sleeve extending into said passage from the opposite side of said loose-leaves and threadedly engaging said screw, and a flange provided on the outer end of said sleeve for clamping engagement with the other outer loose-leaf, the threaded connection between said sleeve and screw being of a tighter fit than the threaded connection between said stud and said socket.

4. In combination with a plurality of stacked loose-leaves having aligned binder post openings therein defining a continuous passage therethrough, a binder post section extending partially through said continuous passage from one side of said loose-leaves and provided with a flange for engagement with one of the outer loose-leaves, said binder post section having a threaded socket therein, a screw provided with a reduced stud in threaded engagement with said threaded socket, an internally screw threaded sleeve extending into said passage from the opposite side of said loose-leaves and threadedly engaging said screw, and a flange provided on the outer end of said sleeve for clamping engagement with the other outer loose-leaf, the threaded connection between said sleeve and screw being of a tighter fit than the threaded connection between said stud and said socket, and kerfs provided in the outer ends of said screw and sleeve.

5. A binder post comprising a post section having a threaded socket in one end and a flange on the opposite end thereof, a screw provided with a reduced threaded stud for threading engagement with said threaded socket, an internally screw threaded sleeve for threading engagement with said screw, and a flange provided on the outer end of said sleeve, the threaded connection between said screw and sleeve being of a tighter fit than the threaded connection between said stud and socket.

In testimony whereof I have affixed my signature.

WALTER F. WOLF.
